US0D1010692S

(12) **United States Design Patent** (10) **Patent No.:** **US D1,010,692 S**
(45) **Date of Patent:** **** Jan. 9, 2024**

(54) **REFRIGERATOR APPLIANCE**

(71) Applicant: **Dometic Sweden AB**, Solna (SE)

(72) Inventors: **Kristoffer Olsson**, Solna (SE); **Samuele Meda**, Solna (SE)

(73) Assignee: **Dometic Sweden AB**, Solna (SE)

(**) Term: **15 Years**

(21) Appl. No.: **29/715,466**

(22) Filed: **Dec. 2, 2019**

Related U.S. Application Data

(62) Division of application No. 29/631,238, filed on Dec. 28, 2017, now Pat. No. Des. 887,459.

(57) **CLAIM**

The ornamental design for a refrigerator appliance, as shown and described.

DESCRIPTION

FIG. 1 is a first upper perspective view of a refrigerator appliance design;

FIG. 2 is a second upper perspective view of the refrigerator appliance design of FIG. 1;

FIG. 3 a front view of the refrigerator appliance design of FIG. 1;

FIG. 4 is a first side view of the refrigerator appliance design of FIG. 1;

FIG. 5 is a second side view of the refrigerator appliance design of FIG. 1; and,

FIG. 6 is a top view of the refrigerator appliance design of FIG. 1.

The broken line disclosure represents unclaimed portions of the refrigerator appliance in which the design is embodied.

1 Claim, 6 Drawing Sheets
